UNITED STATES PATENT OFFICE.

ABRAM H. VAN RIPER AND PATRICK FRANCIS GUTHRIE, OF NUTLEY,
NEW JERSEY.

METHOD OF EXTINGUISHING FIRES.

SPECIFICATION forming part of Letters Patent No. 732,143, dated June 30, 1903.

Application filed March 18, 1902. Serial No. 98,767. (No specimens.)

To all whom it may concern:

Be it known that we, ABRAM H. VAN RIPER and PATRICK FRANCIS GUTHRIE, citizens of the United States, and residents of Nutley, State of New Jersey, have invented certain new and useful Improvements in Means for Extinguishing Fires, of which the following is a full, clear, and exact description.

Our invention relates to means for extinguishing fires which in addition to the blanketing and smothering effect due to the shutting off of the supply of oxygen to the flame, as is accomplished by the extinguishing agencies heretofore known, the oxygen which otherwise would be available to supply the flame is also prevented from reaching the same by being previously absorbed or united with the products of the decomposition of the hyposulfite of soda, and thus its effective action upon the flame destroyed.

In the accompanying drawing we have illustrated one form of apparatus for carrying out our invention which is adapted for use in houses, factories, and public buildings.

The cylinder 1 is attached to the water-supply pipe 2 at any point that may be desired. A sufficient length of hose 3 to reach any required point in the floor-space to be protected is attached to the outlet 4 of the cylinder and is coiled on a reel 5, suspended from the cylinder itself, as by a bracket 6. The cylinder may be of any size desired and is adapted to contain sufficient hyposulfite of soda to be dissolved in twenty-five, fifty, or one hundred gallons of water in the requisite proportions. If the cylinder be of the twenty-five-gallon size, then the cartridge within the same is charged with about five and one-half pounds of hyposulfite, which will form a solution having a specific gravity of about 1.75° Baumé.

Heretofore in the use of fire-extinguishing agents the fluid or water containing the chemical has been sprayed or otherwise forced into contact with the source of combustion and the flames, the extinguishing action being due to the presence of some uncombustible gas, such as carbon dioxid, and to the cooling effect of the fluid, such as water. In such instances it has been customary to use a solution containing or giving off carbon

dioxid or sulfur dioxid formed by the action of sulfuric acid upon marble, or CaCO_3 , or by dissolving hyposulfite of soda in water and allowing the latter to stand until ready for use. Owing to the unstable nature of the solutions of hyposulfite of soda and water when kept ready for use the remaining mixture of sulfite of soda and sulfate of soda does not accomplish the purpose of our invention, and in addition an active corrosive effect upon nearly all objects exposed to its influence is found to exist. Our invention is materially different from these agents, and its operation and effect are that in addition to the blanketing and smothering action we cut off most of the oxygen before it reaches the flame by absorbing the same through chemical action.

Hyposulfite of soda, $\text{Na}_2\text{S}_2\text{O}_3 \cdot 5(\text{H}_2\text{O})$, in its crystalline form containing the excess of water of crystallization when dissolved in water and immediately used upon the flame is decomposed in such a manner as to liberate sodium sulfite and sulfur. The latter then unites with the oxygen of the air and forms sulfur dioxid and ultimately with more oxygen forming sulfuric acid. The sodium sulfite also takes oxygen to form sulfate. The reactions are as follows:

85

By each of these three reactions it will be seen that a large amount of oxygen is taken from the air, and thus prevented from combining with the combustible gases given off by the burning material. By our process of using this salt of sodium the water is not applied to the crystals until demanded, as when a fire occurs, and then the water is caused to rapidly dissolve a quantity of the hyposulfite sufficient to give the reactions as hereinabove set forth. In use the water from the source of supply is made to pass through a suitable receptacle, such as that shown in the accompanying drawing, containing the crystals either

in the form of a cartridge or in bulk. It will be seen that the decomposition of the hyposulfite of soda takes place only at the source of heat or at the flame, and any of the solution which may pass over the fire without coming in contact with it and fall upon delicate fabrics or other destructible material is perfectly harmless, being a neutral solution as regards acids and alkalies. The unused solution upon vaporation results only in the recrystallization of the hyposulfite, which may be easily removed.

The crystals used in our process or method should be as large as convenient. When small crystals or particles are used, the cooling action due to the rapid dissolving of the hyposulfite of soda freezes the mass, and so prevents the free flow of water. It is our purpose to utilize fine crystals of the commercial hyposulfite by dissolving and recrystallizing the same.

Minor changes in the use and adaptation of our invention may be made without departing from the spirit of our invention; but

25 What we claim, and desire to protect by Letters Patent, is—

1. The method of extinguishing fire consisting in applying to the fire a solution containing freshly-dissolved crystals of hyposulfite of soda, substantially as described.

2. The method of extinguishing fire consisting in passing water through a mass of hyposulfite of soda crystals and then immediately applying the resulting solution to the flame or source of combustion, substantially as described.

3. The method of extinguishing fire consisting in rapidly dissolving crystals of hypo-

sulfite of soda in water and then immediately applying the resulting solution to the flame or source of combustion, substantially as described.

4. The method of extinguishing fire through the medium of sodium sulfite and sulfur, comprising the forming of a solution from hyposulfite of soda by the application thereto of running water, then immediately conveying the same to the burning material whereby the oxygen immediately surrounding the source of combustion is absorbed, substantially as described.

5. The method of extinguishing fire comprising the forming of a solution by passing running water through a confined body of crystals of hyposulfite of soda, then immediately conveying the solution to the burning material whereby sulfur and sulfite of soda are formed by the heat and the immediately surrounding oxygen absorbed thereby, substantially as described.

6. The method of extinguishing fire through the medium of sodium sulfite and sulfur, comprising the forming of a solution from hyposulfite of soda by the application thereto of running water so that said solution will have a specific gravity of substantially 1.75° Baumé, then immediately conveying the same to the burning material substantially as described.

In witness whereof we have hereunto set our hands this 4th day of March, A. D. 1902.

ABRAM H. VAN RIPER.
